UNITED STATES PATENT OFFICE

HENRY HOWARD, OF MIDDLETOWN, RHODE ISLAND, ASSIGNOR, BY MESNE ASSIGNMENTS, TO THE GRASSELLI CHEMICAL COMPANY, OF CLEVELAND, OHIO, A CORPORATION OF DELAWARE

STORAGE DEVICE FOR VOLATILE LIQUIDS

Original application filed November 5, 1926, Serial No. 146,544. Divided and this application filed July 16, 1928. Serial No. 293,082.

This invention relates to apparatus for storage and delivery to the places used of volatile liquids such as aqua ammonia, gasoline, benzol, etc.

5 This application is a division of my co-pending application Serial No. 146,544, filed November 5, 1926.

According to the present invention, the automatic compensation for variations in 10 pressure due to temperature changes and/or to the transfer of liquid to or from the storage tank, is obtained by the use of a pair of ball check valves which are so associated with the storage tank that one or the other 15 valve opens when the pressure in the tank rises above or falls below the normal pressure.

One embodiment of the invention, as applied to a plant for oxidizing ammonia, is 20 illustrated in the accompanying drawings, in which

Fig. 1 is a diagrammatic illustration of certain elements of the ammonia treating plant,

25 Fig. 2 is a vertical section through one of the ball check valves.

In the drawings, the numeral 1 indicates a storage tank from which aqueous ammonia may be pumped to the supply tank 2 by suitable system of conduits and pumps, not shown. From the supply tank 2, the liquid passes to the ammonia stripping column 3 through pipe 4 and valve 5.

The supply tank 2 is provided with a dome 35 or upward extension 6 which is connected to the upper portion of storage tank 1 by the breather pipe 7.

The elements of the ammonia oxidizing plant, as so far described, are or may be of 40 any conventional construction.

In accordance with the present invention, the upper portion of the storage tank 1 is connected to a vent space by valved conduits which provide an absolute seal for volatile 45 gases evolved from the stored liquid so long as the pressure within the tank remains approximately normal, and which permit the flow of gases to or from the tank as the pressure within the same tends to rise above or 50 fall below its normal value.

As shown in Fig. 1, a pair of ball check valves 9, 10 are connected between the breather pipe 7 and the upper portion of the stripping column 3. Pipes 11 and 12 lead from the inlet side of valve 9 to the breather 51 pipe 7 and to the outlet side of valve 10, respectively, and in a similar manner the inlet side of valve 10 is connected to the stripping column 3 and the outlet side of valve 9 by pipes 13, 14, respectively. 66

Each check valve takes the form of a chamber 15 having an inlet port 16 in its lower wall and an outlet port 17 in a side wall. A ball valve 18, which may be of earthenware, normally rests upon a valve seat 19, 65 which also may be of earthenware, as illustrated in Fig. 2, and fixed to the bottom of the chamber 15 by cement 20, or the like. The chamber 15 is provided with a suitable top closure, such, for example, as the bolted 70 on cover plate 21.

If the pressure within the storage tank 1 rises above its normal or desired value, the valve 9 is raised from its seat and the pressure is relieved, the vapors passing through breather pipe 7, pipe 11, valve 9, and pipes 14, 13, to the stripping column. If, on the other hand, the storage tank is cooled, thereby developing a subnormal pressure in the breather pipe 7, the valve 10 opens under 75 the pressure existing in stripping column 3, and vapors pass from column 3 through pipe 13, valve 9, pipes 12, 11 and breather pipe 7, into the storage tank. 80

My invention, therefore, automatically 85 maintains the pressure to which storage tank 1 is subjected within certain predetermined limits. By properly proportioning the weights of the ball valves, the conditions of pressure or partial vacuum in the vapor space 90 of the tank can be so controlled that evaporation is lessened or increased until a danger point is reached, one of the valves then opening to effect automatic relief.

The valves and the venting or relief conduit are, of course, constructed of material 95 which will not be attacked by the stored liquid or by gases evolved therefrom. I have found that earthenware balls are satisfactory for use in the handling of stored aqueous am-

monia, but it will be understood that other materials may be employed with aqueous ammonia and with other liquids.

It is to be noted that the ball type of check valve is particularly desirable, since the rolling movement of the valve on its seat as it opens and closes will keep the valve seat clean.

It is to be understood that the invention is not limited to the particular apparatus which is illustrated and described herein, as many changes which may be made in the construction and arrangement of the oppositely arranged check valves fall within the spirit of my invention as set forth in the following claims.

I claim:

1. Apparatus for the handling of volatile liquids comprising a storage tank, a chamber, a working conduit connecting said tank and said chamber, a by-pass conduit connecting said tank and said chamber and a pair of check valves oppositely disposed in said second-named conduit.
2. Apparatus for the handling of volatile liquids comprising a storage tank, a supply tank and a chamber for utilizing said liquids, conduits serially connecting said tanks and chamber, a second conduit connected between said storage tank and said chamber and a pair of check valves oppositely disposed in said conduit, the outlet of each valve being connected to the inlet side of the other of said valves.
3. In apparatus for handling volatile liquids, a storage tank, a chamber for utilizing said liquids, a breather conduit connecting said tank and said chamber, a plurality of check valves each including a chamber having an inlet and an outlet, a seat of ceramic material and a ball of similar material, a conduit leading from said breather conduit to the inlet side of one of said valves, a conduit leading from said chamber to the inlet side of another of said valves and conduits connecting the outlet of each of said valves with the inlet of the other of said valves.
4. In apparatus for handling volatile liquids, a storage tank, a chamber for utilizing said liquids, means for connecting said tank and said chamber, and means operative upon the existence of an abnormally high or abnormally low pressure in said tank, for providing communication between said tank and said chamber in parallel to said connecting means.

In testimony whereof, I affix my signature.
HENRY HOWARD.
